FLAVIUS J. UNDERWOOD, OF ROCK ISLAND, ILLINOIS.

Letters Patent No. 96,057, dated October 19, 1869.

IMPROVEMENT IN ROTARY COULTERS.

The Schedule referred to in these Letters Patent and making part of the same.

To all whom it may concern:

Be it known that I, FLAVIUS J. UNDERWOOD, of Rock Island, in the county of Rock Island, and State of Illinois, have invented certain new and useful Improvements in Rotary Coulters; and I do hereby declare that the following is a full, clear, and exact description thereof, reference being had to the accompanying drawings, making part of this specification, and to the letters of reference marked thereon, like letters indicating like parts wherever they occur.

To enable others skilled in the art to construct and use my invention, I will proceed to describe it.

My invention relates to rotary coulters for plows; and

It consists in a novel manner of constructing the hub, whereby it can be screwed together, and made to clamp and hold the coulter-blades, as hereinafter more fully explained.

In the accompanying drawings—

Figure 1 is a transverse vertical section;

Figure 2 is a side elevation of one of the parts detached; and

Figure 3 is an end view of one of the parts of the hub.

In constructing rotary coulters, it is necessary to secure them to the shaft upon which they revolve, in such a manner that the blade shall revolve in a true vertical plane.

Heretofore this has been accomplished in various ways, but always with considerable trouble and expense, and more or less imperfectly.

The object of my present invention is to provide a simple, cheap, and efficient means of securing the blade, so that it shall be held firmly and truly in position.

To accomplish this, I make a cast-iron hub, of two parts, B and C, of the form represented in the drawings.

These parts consist of a circular plate, each having on their exterior sides a projecting hub, F, which is made with a series of angles or flat faces on its sides, so as to be readily grasped in a vise or by a wrench, and also with a hole extending centrally through it, for the reception of a shaft, E, as represented in fig. 1.

One of these parts, B, is provided also with a central circular projection, D, on its inner face, as shown

in fig. 2, on the exterior of which is formed a screw-thread, as there shown.

The other part, C, is provided with a corresponding socket, having on its inner face a corresponding screw-thread, so that the two parts, B and C, may be screwed together, as represented in fig. 1.

These parts B and C are cast with the screw-threads ready formed thereon, so that they can be screwed together just as they come from the mould, thus saving the labor and expense of cutting the threads by machinery, as is usually done.

It is, however, obvious that this plan of constructing the hub is equally applicable to hubs made either of wrought or cast-iron, and having the threads cut by proper tools, though I prefer to cast them complete, as above stated, for the reason that it is cheaper so to do.

With a hub thus constructed, it is only necessary to form the disk or blade A in the usual style, with its central hole large enough to slip on to the projection D, and after having placed it thereon, screw the two parts, B and C, together, as shown in fig. 1, the blade A being tightly clamped between the flanges of the two parts, and held firmly and truly in position, the flanges serving also to brace and stiffen the blade at its central portion.

These flanges may be made to extend as far out on the blade A as desired, and by this means a very thin blade may be used, thus saving material, and labor in grinding it to an edge.

The hub may be made fast on the shaft E, the latter turning in its bearings in the stem that supports it, or the shaft may be made fast in its stem, and the hub be arranged to turn loosely on the shaft, as preferred.

In this manner I construct a very simple, cheap, and efficient device, admirably adapted to the purpose for which it is intended.

Having thus described my invention,

What I claim, is—

A rotary coulter, having a hub, composed of the two parts, B and C, constructed so as to screw together and clasp the blade A between them, substantially as described.
